UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

SCREEN OR SEPARATOR.

1,072,879.

Specification of Letters Patent. Patented Sept. 9, 1913.

Application filed January 6, 1913. Serial No. 740,415.

To all whom it may concern:

Be it known that I, THOMAS J. STURTEVANT, a citizen of the United States, residing at Wellesley, in the county of Norfolk and State of Massachusetts, have invented or discovered certain new and useful Improvements in Screens or Separators, of which the following is a specification, reference being had therein to the accompanying drawings.

This invention relates to screens or separators, and more particularly to that class thereof in which a fine output of material is obtained by the use of fine mesh screens.

The invention has for its object to increase the output and expedite the screening operation by the use of air currents which will pass through the screen clothing and vibrate the same more or less; these air currents being preferably of an alternating, pulsating or reversing character so that when moving in one direction they will tend to clear the meshes of the screen of material which may be lodged thereon or therein, and while moving in the opposite direction will tend to suck or draw fine material through the meshes of the screen clothing at a more rapid rate than would result simply from gravity, thereby expediting the screening operation and increasing the output. These pulsating air currents are preferably produced by air-agitating devices located below the screens and adjacent thereto, and which air-agitating devices may be of any suitable character, as will be hereinafter more fully indicated.

In the accompanying drawings, in which similar reference numerals denote similar parts, Figure 1 is a side view, partly in section, of a screen or separator embodying one of the preferred mechanisms for carrying the invention into effect, and Fig. 2 is a front elevation of the same. Fig. 3 is a sectional side elevation of a screen or separator embodying a different form of the invention from that shown in Fig. 1, and Fig. 4 is a front view of the separator shown in Fig. 3. Fig. 5 is a sectional view illustrating still another embodiment of the invention. Figs. 6 and 7 are detail views of the fan belts shown in Fig. 3.

Referring to Figs. 1 and 2 of the drawings, 12 denotes a suitable framework sup-

porting a casing 13 which will preferably comprise a hinged cover 14. At the upper part of the said framework or casing is mounted a hopper 15, to receive the incoming material, and within said hopper is a feed wheel 16 which will be rotated at a speed suitable to properly feed the material to the screen. The said screen will preferably consist of fine wire mesh screen clothing 17 stretched on a suitable frame 18 properly supported within the chamber of the separator and preferably in an inclined position.

Mounted on suitable supports or brackets 19 secured to the screen frame is a driving shaft 20 provided with a crank 21, said driving shaft being furnished with a pulley 22 which may be belted to any suitable source of power. The crank 21 is connected by a pitman 23 with a piston rod 24, on which are mounted a series of pistons 25 arranged below and adjacent to the fine mesh screen 17, said pistons reciprocating in chambers formed by partitions 26. These chambers in which the pistons reciprocate have openings at their bottoms for the discharge of the screened material into the receiving hopper below. The piston rod passes at its lower end through a steadyng and guiding bracket 27 mounted on the casing 13.

In the form of the invention just described the reciprocating pistons, when the machine is in operation, will cause pulsating or alternating air currents, more or less of which will pass through the fine mesh screen in opposite directions, as the pistons move back and forth in the piston chambers, for the purpose of clearing the screen when the air currents are upward, and also for the purpose of sucking or drawing fine material through the screen when the air currents are downward; this operation gently vibrating the fine mesh screen and expediting the screening operation by alternately clearing the screen clothing and sucking fine material through the same, so that the output of the machine will be greatly increased over what would result merely from the action of gravity.

In the form of the invention shown in Figs. 3 and 4 the air-agitating device, to effect the reversing or pulsating air currents, comprises fan belts 28 running over

2
suitable pulleys 29, the said fan belts being provided with reversely inclined wings or fans 30 and 31 arranged below but adjacent to the fine mesh screen 17. When the pulleys are rotated in the direction indicated by the arrows the inclined wings or fans 30 will have a tendency to force the air upward against and through the fine mesh screen, while the wings or fans 31 will have a tendency to draw air downward, thereby producing alternating or pulsating air currents which will gently vibrate the fine mesh screen and operate to clear the same and to draw fine material therethrough. The pulleys 29 are driven from the power shaft 32 which is provided with a pulley 34 connected by a belt 33 with a pulley 35 on the shaft 36 on which the lower pulleys 29 are mounted.

20 In the form of the invention shown in Fig. 5 the alternating air currents are caused by vibrating fans 37 mounted on rock shafts 38 which may be operated in any suitable manner, as by a pitman 39 connecting one 25 of a series of gears 42 on said shafts with a crank 40 on a suitable driving shaft 41.

In all of the different forms of the invention shown the screens 17 and the frames supporting the same are fixed or stationary, 30 in contradistinction to shaking or rotary movable screens. Also in all of the forms of the invention shown the air-stirring or air-forcing elements are separated from or out of contact with the screens, so as not to rub 35 against them, which would result in serious wear and injury.

The movements of the air agitating devices may be at any desired speeds, and may be, and will preferably be more or less irregular and such will be the case in the construction shown for example in Fig. 1 where the air agitating pistons are operated from a crank in such a manner that their movements will be more or less irregular.

45 The air-agitating devices, operating in accordance with this invention, will preferably be so disposed as to cause the air currents to strike or pass through the screen clothing at an angle inclined to the plane of 50 the latter, so that by thus giving a slant to the air currents the effect will be to make the working size of the screen meshes finer, like the effect produced by changing a horizontal screening surface to an inclined position. This result is effected, in the several 55 different forms of the invention herein shown, by so arranging and operating the air-stirring devices that the wings or air-stirring members thereof are caused to travel 60 in planes parallel to the planes in which the screens are disposed, or approximately so, in performing their pulsating air-stirring movements. Also the invention will preferably be employed in connection with inclined screens, as shown in Figs. 1 and 3,

but it may also be used in connection with a horizontal screen, as shown in Fig. 5.

It will be obvious that in the several forms of the invention herein shown and described, and in which, in each form of the invention, the air agitating device comprises a plurality of air-forcing elements spaced apart from each other, air currents will be caused to pass through different portions of the screen in opposite directions at the same time. For example, in the form of the invention shown in Fig. 1 the pistons 25, working in compartments formed by the partitions 26, will force the air upward on one side of each piston and will cause a downward suction of air on the opposite side thereof; and this simultaneous upward and downward movement of air currents through different portions of the screen will, it is obvious, result in the operation of the other forms of the invention shown and described.

The invention is not to be understood as being limited to the details of construction herein shown and described, as these may be varied widely, within the limits of mechanical skill, without departing from the essence or scope of the invention as the same is defined by the claims hereunto appended.

Having thus described my invention I claim and desire to secure by Letters Patent:

1. In a separator, the combination with a fixed or stationary screen, of an air-stirring device comprising air-stirring members arranged adjacent to but separated from said screen, and means for causing said air-stirring members to travel in a plane approximately parallel to that in which the said screen is disposed in performing their air-stirring movements.

2. In a separator, the combination with a screen, of a reciprocating air-stirring device comprising air-stirring members arranged adjacent to but separated from said screen, and means for causing said air-stirring members to travel in a plane approximately parallel to that in which the said screen is disposed in performing their air-stirring movements.

3. In a separator, the combination with a fixed or stationary screen, of an air-stirring device comprising air-stirring members arranged beneath and adjacent to but separated from said screen, and means for causing said air-stirring members to travel in a plane approximately parallel to that in which the said screen is disposed in performing their air-stirring movements.

4. In a separator, the combination with an inclined screen, of an air-stirring device comprising air-stirring members arranged adjacent to but separated from said screen, and means for causing said air-stirring members to travel in a plane approximately

parallel to that in which the said screen is disposed in performing their air-stirring movements.

5. In a separator, the combination with an inclined screen, of an air-stirring device comprising air-stirring members arranged beneath and adjacent to but separated from said screen, and means for causing said air-stirring members to travel in a plane approximately parallel to that in which the said screen is disposed in performing their air-stirring movements for the production of pulsating air currents which pass reversely or alternately through the screen clothing.
10. In a separator, the combination with an inclined screen, of a reciprocating air-stirring device comprising air-stirring members arranged beneath and adjacent to but separated from said screen, and means for causing the said air-stirring members to travel in a plane approximately parallel to that in which the said screen is disposed in performing their air-stirring movements for the production of pulsating air currents which pass reversely or alternately through the screen clothing.
15. In a separator, the combination with an inclined screen, of an air-agitating device comprising a plurality of reversely-acting air-forcing elements arranged adjacent to but separated from said screen and spaced apart from each other, and means for moving said air-forcing elements through different portions of said screen simultaneously.

20. In a separator, the combination with an inclined screen, of an air-agitating device comprising a plurality of reversely-acting air-forcing elements arranged adjacent to but separated from said screen and spaced apart from each other, and means for moving said air-forcing elements through different portions of said screen simultaneously.

25. In a separator, the combination with an inclined screen, of an air-agitating device comprising a plurality of reversely-acting air-forcing elements arranged adjacent to but separated from said screen and spaced apart from each other, and means for moving said air-forcing elements through different portions of said screen simultaneously.

30. In a separator, the combination with an inclined screen, of an air-agitating device comprising a plurality of reversely-acting air-forcing elements arranged adjacent to but separated from said screen and spaced apart from each other, and means for moving said air-forcing elements through different portions of said screen simultaneously.

35. In a separator, the combination with an inclined screen, of an air-agitating device comprising a plurality of reversely-acting air-forcing elements arranged adjacent to but separated from said screen and spaced apart from each other, and means for moving said air-forcing elements through different portions of said screen simultaneously.

40. In a separator, the combination with an inclined screen, of an air-agitating device comprising a plurality of reversely-acting air-forcing elements arranged adjacent to but separated from said screen and spaced apart from each other, and means for moving said air-forcing elements through different portions of said screen simultaneously.

screen and spaced apart from each other, and means for moving said air-forcing elements; whereby reversely moving air currents will be caused to pass in opposite directions through different portions of said screen simultaneously.

45. In a separator, the combination with an inclined screen, of an air-agitating device comprising a plurality of reversely-acting air-forcing elements arranged adjacent to but separated from said screen and spaced apart from each other, and means for moving said air-forcing elements; whereby reversely moving air currents will be caused to pass in opposite directions through different portions of said screen simultaneously.

50. In a separator, the combination with an inclined screen, of an air-agitating device comprising a plurality of reversely-acting air-forcing elements arranged below and adjacent to but separated from said screen and spaced apart from each other, and means for moving said air-forcing elements; whereby reversely moving air currents will be caused to pass in opposite directions through different portions of said screen simultaneously.

55. In a separator, the combination with an inclined screen, of an air-agitating device comprising a plurality of reversely-acting air-forcing elements arranged below and adjacent to but separated from said screen and spaced apart from each other, and means for moving said air-forcing elements; whereby reversely moving air currents will be caused to pass in opposite directions through different portions of said screen simultaneously.

60. In a separator, the combination with an inclined screen, of an air-agitating device comprising a plurality of reversely-acting air-forcing elements arranged below and adjacent to but separated from said screen and spaced apart from each other, and means for moving said air-forcing elements; whereby reversely moving air currents will be caused to pass in opposite directions through different portions of said screen simultaneously.

65. In a separator, the combination with an inclined screen, of an air-agitating device comprising a plurality of reversely-acting air-forcing elements arranged below and adjacent to but separated from said screen and spaced apart from each other, and means for moving said air-forcing elements; whereby reversely moving air currents will be caused to pass in opposite directions through different portions of said screen simultaneously.

70. In a separator, the combination with an inclined screen, of an air-agitating device comprising a plurality of reversely-acting air-forcing elements arranged below and adjacent to but separated from said screen and spaced apart from each other, and means for moving said air-forcing elements; whereby reversely moving air currents will be caused to pass in opposite directions through different portions of said screen simultaneously.

75. In a separator, the combination with an inclined screen, of an air-agitating device comprising a plurality of reversely-acting air-forcing elements arranged below and adjacent to but separated from said screen and spaced apart from each other, and means for moving said air-forcing elements; whereby reversely moving air currents will be caused to pass in opposite directions through different portions of said screen simultaneously.

In testimony whereof I affix my signature, in presence of two witnesses.

THOMAS JOSEPH STURTEVANT.
